PIPE RACKING APPARATUS

John E. Whited, Shawnee, Okla.

Application October 10, 1945, Serial No. 621,486

2 Claims. (Cl. 214—1)

1

The invention pertains to pivoted arms for handling the upper ends of drill pipe or tubing standing in an oil well derrick.

When well pipe is brought out of an oil well it is broken off in sections and these sections are stood on end, or "racked" at one side of the oil well derrick. A fourble board or platform is provided in the upper portion of the derrick, upon which a workman may stand to swing the upper end of the pipe "stands" into a position in which they tiltably recline against the derrick, and also to swing such upper ends out from the sides of the derrick into a position in which they may be engaged by usual well pipe elevators. These well pipe "stands" are very heavy, usually consisting of three or four sections, and it is therefore quite a chore for a man to properly handle the upper ends of the "stands" quickly and safely.

The present invention includes an arm pivoted to the fourble board or platform on a vertical axis, so that it may act as a means for engaging and holding the upper end of a drill pipe "stand" while the "stand" is being swung into or out of "racked" position.

It is a principal object of the present invention to provide a racking apparatus for the purpose set forth, which will engage and steady the upper end of a pipe "stand" while it is being moved from an inclined or "stacked" position to a substantially vertical position where it may be engaged by a usual pipe elevator, and vice versa.

Another object is to provide apparatus of this class which may be folded into a retrieved position when not in use so that it will not interfere with other operations in and around the oil well derrick.

A further object is to provide a pipe racking arm which may be swung in a horizontal plane from a position in which it projects toward the center of the derrick, to a horizontal position in which it projects along one side of a derrick.

Another object is to provide a pipe racking arm which may be latched in either of the two last above mentioned positions.

A still further object is to provide an arm of this class which is spring actuated to normally return to a retrieved position.

Yet another object of the invention is to provide a pipe racking apparatus for the purpose as set forth which is comparably simple in construction, and which may be attached to any usual fourble-board or derrick platform.

Other objects will be apparent from the following description when taken in conjunction with the accompanying two sheets of drawings, wherein:

Fig. 1 is a perspective view of a suitable derrick platform with the arm of the present invention shown operatively mounted thereon;

Fig. 2 is a similar view with a portion of the arm folded over the platform; and,

Fig. 3 is a fragmentary vertical sectional view 10 through the arm and platform.

Like characters of reference designate like parts in all the figures wherein they occur.

In the drawings:

The reference numeral 1 indicates, as a whole, 15 a flat fourble-board which is usually positioned in the upper portion of a well derrick for providing support for a derrick worker, so that he may rack or un-rack the upper end of a well pipe "stand," and so that he may latch or un-latch 20 usual well pipe elevators from the "stands." The board 1 is provided at one side with a plurality of spaced legs or fingers 2 between which the upper ends of the pipe "stands" 3 are rested when the pipe is "stacked" or "racked." The fourble-board 1 could well be a type of derrick platform 25 which often forms a part of a gin-pole-type of well derrick, if desired.

The invention, per se, consists substantially of 30 a flat metal plate 4 adapted to be rigidly attached by detents 5 adjacent one edge of the fourble-board 1. The plate 4 has a centrally located through bore which journals for rotation a pintle or pivot pin 6. The upper portion of the pintle 6 is keyed to, or made integral with, a flat fitting 35 7 having laterally spaced parallel upstanding ears or brackets 8 formed as a part thereof. A grease fitting 9 may be provided in the upper end of the pintle 6 for lubricating the bearing thereof through suitable passages, if desired. The ears 8 of the fitting 7 are horizontally perforated to receive a hinge pin 10.

Pivoted upon the pin 10 is a heavy metal casting or hinge member 11 which is rigidly connected to a channel iron arm 12 having upright side flanges 13. The free end 14 of the arm 12 is equipped with oppositely disposed arcuate pipe clamping elements 15 which are preferably made of strap-iron.

Each of the clamping elements 15 has a straight portion 16 which extends along the outside surface of one of the side flanges 13 of the arm 12. The straight portions 16 are each connected to an adjacent flange 13 by a plurality of bolts 17, each of which is surrounded by an expansion 50 55 spring 18. The springs 18 permit the arcuate

end portions of the clamping elements to be moved away from each other a sufficient distance to permit the entry therebetween of one of the "stands" 3 of well pipe.

As illustrated in Fig. 2, the arm 12 may be folded back over the plate 4 with the hinge pin 10 acting as an axle. When in this position, the arm does not interfere with any of the usual well derrick operations.

The upper surface of the plate 4 is equipped with two upstanding ears 19, between which is pivotally mounted upon a pin 20 a hooked latch member 21. The latch member 21 may be operated by the worker's foot. The hooked end of the latch member 21 is adapted to engage over the flange 13 of the arm 12 for retaining the same in the full line position of Fig. 1. A suitable helical spring, not shown, is provided around the pin 20 for urging the hooked end of the latch member 21 toward its latched position.

As best illustrated in Fig. 1, the arm 12 may be moved on the pintle 6 from the position shown in solid lines, to that illustrated in dotted lines. When in the dotted line position, the arm will steady the "stand" 3 so that usual pipe elevators may be engaged or disengaged therefrom. A suitable stop member 25 is provided to limit the pivotal movement of the arm 12 in an obvious manner. When the arm is swung to the solid line position, the "stand" may be manually removed from between the clamping elements 15 so that it may be "racked" between the fingers 2 in an obvious manner.

The depending end of the pintle 6 is surrounded by a suitable helical spring 22 (Fig. 3) which acts to normally urge the arm 12 toward the solid line position of Fig. 1. A bearing plate 23 is provided between the upper end of the spring 22 and the lower surface of the plate 4.

It is thought that operation of the device will be apparent, to those versed in the art, without further description.

I claim:

1. In apparatus for handling the upper ends of well pipe "stands," the combination with a stationary platform located above a derrick floor, of: a fitting pivotally mounted directly upon the platform for horizontal swinging movement with relation thereto; a rigid arm; vertically projecting longitudinally extending side flanges carried by the arm; a hinged connection between the fitting and one end of the arm whereby the arm may be folded upwardly over the platform into inoperative position; a pair of laterally movable fingers each having a longitudinal portion lying flatly

against the outside surface of one of said flanges, and each having an arcuate portion projecting longitudinally beyond the free end of said arm, said arcuate portions confronting each other for engaging opposite surfaces of upper portions of said pipe "stands"; a plurality of bolts extending laterally through the flat portion of one of said fingers, and through the adjacent flange of said arm, said bolts projecting beyond the flange toward the longitudinal axis of the arm; an expansion spring around the projecting portion of each bolt; and a nut on each bolt for holding its spring under compression whereby said arcuate portions are resiliently urged into frictional engagement with said "stands."

2. In apparatus for handling the upper ends of well pipe "stands," the combination with a stationary platform located above a derrick floor, of: a fitting pivotally mounted directly upon the platform for horizontal swinging movement with relation thereto; a rigid arm; vertically projecting longitudinally extending side flanges carried by the arm; a hinged connection between the fitting and one end of the arm whereby the arm may be folded upwardly over the platform into inoperative position; a latch on the platform for latching the arm against horizontal swinging movement with relation thereto; a pair of laterally movable fingers each having a longitudinal portion lying flatly against the outside surface of one of said flanges, and each having an arcuate portion projecting longitudinally beyond the free end of said arm, said arcuate portions confronting each other for engaging opposite surfaces of upper portions of said pipe "stands"; a plurality of bolts extending laterally through the flat portion of one of said fingers, and through the adjacent flange of said arm, said bolts projecting beyond the flange toward the longitudinal axis of the arm; an expansion spring around the projecting portion of each bolt; and a nut on each bolt for holding its spring under compression whereby said arcuate portions are resiliently urged into frictional engagement with said "stands."

JOHN E. WHITED.
